UNITED STATES PATENT OFFICE.

ALEXANDER ROY MACDONALD, JR., OF MONTREAL, CANADA.

ORE-SEPARATOR.

SPECIFICATION forming part of Letters Patent No. 664,768, dated December 25, 1900.

Application filed December 27, 1897. Renewed December 3, 1900. Serial No. 38,561. (No model.)

To all whom it may concern:

Be it known that I, ALEXANDER ROY MACDONALD, Jr., a citizen of the Dominion of Canada, residing in the city and district of 5 Montreal, Province of Quebec, Canada, have invented certain new and useful Improvements in Ore-Separators; and I do hereby declare the following to be a full, clear, and exact description of the invention, such as will 10 enable others skilled in the art to which it appertains to make and use the same.

My invention relates to improvements in ore-separators.

One object of my invention is to provide 15 a device of this character in which the ore after being crushed is passed through a sluiceway in such manner that eddies will be formed in which the ore and water will be temporarily held subject to the action of the 20 amalgamating medium.

A further object is to provide a device in which the ore is subjected to the action of the amalgamating medium in its passage through the sluiceway for its entire length, forming a 25 succession of traps for the metal.

A further object is to provide a device in which the water after passing through the sluiceway is caught up and passed back to be used again.

30 A further object is to provide a collapsible ore-separator which can be readily transported and placed in position with great ease.

A further object is to provide a device which will be durable in construction, accurate 35 and simple in its operation, and which can be manufactured at a comparatively low cost.

To these ends my invention consists in the improved construction and combination of 40 parts hereinafter fully described, and particularly pointed out in the claims.

In the drawings, in which similar letters of reference indicate similar parts in all of the views, Figure 1 is a plan view of my improved 45 ore-separator. Fig. 2 is a side elevation of the same. Fig. 3 is a sectional view of the hopper. Fig. 4 is a sectional view of the middle section, showing the brushes and drawer-trap. Fig. 5 is a sectional view showing the 50 construction of the eddy-formers, together with the trap therefor. Fig. 6 is a similar

view showing a removable trap. Fig. 7 is a view of the lower section and the pan. Fig. 8 is a sectional view of the pan.

Numerous ore separators and amalgamators have been provided for the purpose of extracting precious metals, and especially gold, from the ore, and in most of these constructions the use of mercury as an amalgamator has been found to be the best. In these 55 constructions, however, the ore and water have been passed through the sluice-box in such manner that a quantity of the gold has escaped by reason of the fact that the progress of the water through the separator has been 60 comparatively steady and does not allow the ore to remain at rest sufficient time to allow the gold to be amalgamated with the mercury. Previous constructions have also been made in such manner as to be cumbersome 65 and inconvenient for transportation. Another disadvantage has appeared in that when the water has been passed through the sluiceway it is allowed to pass away and be wasted, a disadvantage that is very costly, especially 70 when the separator is used in a region where water is scarce. It is the purpose of the present device to obviate these disadvantages, and in so doing I provide the following-described device:

80 A designates a sluice having the support, composed of side sections *a* and end sections *a'*. The sections *a* are made in convenient lengths and are adapted to be put together and the end pieces placed thereon, the entire 85 forming a frame light in weight, but by reason of the use of the braces *a*² of exceedingly strong and durable construction. The frame is adapted to be set at an angle, being supported by any suitable support, such as stones, 90 beams, &c. The side sections *a* are held against any liability of spreading by means of rods *a*³.

Mounted within the supporting-sections *a* and seated on the rods *a*³ is the sluiceway 95 *B*, formed of the sections *b b' b*². These sections are adapted to be fitted together in such manner as will form a continuous sluiceway. The section *b*² has one of its sides rounded, as best shown in Fig. 7, for a purpose hereinafter described. Each section *b b' b*² is provided with a series of eddy-formers *b*³, formed

as shown in Fig. 1, each eddy-former consisting of a semicircular band b^4 , secured to the bottom of the section and partially surrounding a suitable depression b^5 , the central portion of the band being provided with an extension b^6 , adapted to partially surround a depression b^7 , extending downward to a greater depth than the depression b^5 . If desired, the depression b^7 may have its bottom open, as shown in Fig. 6, in which case a cap b^8 should be provided.

By means of the above construction it will be apparent that the passage of the water and ore downward through the sluiceway will be continually interrupted and they will be compelled to pass into each series of bands and be forced in a circular direction, forming an eddy in each band, the central part of which is directly over the depression b^5 . As the eddy continues, it will be obvious that the crushed ore will be held in suspension and the minerals be gradually forced into the depressions b^7 , which are adapted to contain mercury. The constant whirling movement of the ore and water, as shown by the arrows in Fig. 1, will continually subject the ore to the action of the mercury and will in addition cause the ore to be broken up into finer particles, and thus cause a greater amount of the minerals to be caught up by the mercury.

The central section b' is provided at each end with semicircular recesses b^9 , having openings b^{10} , the openings leading into a suitable drawer b^{11} , adapted to be slidably mounted in guideways, as best shown in Fig. 4. The drawers b^{11} are adapted to contain mercury, into which the crushed ore and water are swept by means of brushes b^{12} . The brushes b^{12} are formed in sections and held together when in use by suitable means. A shaft b^{13} is mounted in suitable bearings b^{14} , preferably ball-bearings, to which shafts the brushes b^{12} are connected. Each shaft is provided with suitable sprocket-wheels b^{15} and they are connected together, as shown in Fig. 1. The shafts are rotated by suitable means, they in turn operating the brushes. It will be apparent that the brushes will sweep the crushed ore and water into the recesses, where the ore is subjected to the action of the mercury, and then passed out, where it again encounters the action of the eddy-formers, as hereinbefore described.

The section b is provided with a removable hopper C , composed of the flared top c and a central chamber c' . A suitable removable sieve c^2 is mounted between the top c and chamber c' . The central chamber c' is provided with a suitable brush c^3 , formed similar to the brushes b^{12} , adapted to be rotated by means of a sprocket secured to the end of the shaft c^4 and connected to the sprockets on the shaft b^{13} . Below the brush c^3 is secured a removable sieve c^5 .

The operation of the device as above described is as follows: The water, which is kept in a suitable tank, (not shown,) is turned

into the top c , into which the crushed ore has been placed, the water and crushed ore passing through the sieve c^2 into the central chamber c' , in which the brush c^3 spreads the crushed ore and forces it through the sieve c^5 onto the sluiceway, down which it passes and becomes subjected to the action of the eddy-formers and brushes, as heretofore described. After the ore has passed the lower series of eddy-formers in section b^2 of the sluiceway it is forced to one side of the sluiceway by the rounded end, from which it passes into the pan D , mounted at the lower end of the frame. The pan D is preferably formed as shown in Figs. 7 and 8 and consists of the main portion d and the drip-flange d' . The bottom of the main portion d is preferably formed with cup-shaped depressions d^2 , adapted to contain mercury. The drip-flange d' is formed to extend above the top of the main portion d and has its bottom arranged at a slight angle, the lowest point being provided with an opening d^3 . The pan D is so arranged that as the ore passes from the opening at the lower end of the sluiceway it is forced toward one side of the pan, the force being sufficient to force it around the pan with a circular motion, forming a large eddy, the central part being practically without movement, the particles being held in suspension, the heavier particles dropping to the bottom and swept into the depression d^2 . As the depth of water increases it flows over the top of the main portion into the drip-flange d' , from where it is pumped by means of a suitable pump E , actuated by suitable gearing connected to the brush-actuating mechanism and having an operative connection with the flange d' , into the tank containing the water-supply to be used in passing other ore over the sluiceway. In this manner no water is wasted, it continuing in use until the ore is entirely amalgamated.

As the frame and sluiceway are all formed in sections and the hopper is removable from the sluiceway, it will be apparent that the entire outfit can be taken apart and put into a compact form, making it easy to be transported, the small parts, brushes, &c., being placed inside of the central chamber of the hopper.

The brushes are preferably formed in sections, as hereinbefore set forth, in order that they may be readily packed, and while any suitable brush may be used I preferably use what is known as a "wire brush." The bristles are preferably arranged in spiral form or, as shown in Fig. 1, with a "zigzag" movement across the brush, causing them to force the ore backward and forward to better aid in its amalgamation.

Any suitable power may be used to actuate the mechanism—such as hand, steam, wind, water, or animal—the one most convenient being used and the connection being made to one of the shafts b^{13} .

The entire outfit is to be made of some suit-

able material which is light in weight yet of great tensile strength, such as aluminium, to enable it to be readily transported.

The sides of the pan D are provided with 5 annular indentations d^5 to prevent the ore from rising in the pan while having its circular movement.

Having thus described my invention, what I claim as new is—

10 1. A sluiceway for ore-separators, comprising a sluice; a series of depressions formed therein; and bands extending vertically therefrom in series, said bands extending around the lower side of said depressions, the ends 15 of bands of alternate series being joined, whereby the material passing over said sluice will be given a backward rotary movement, said movement being in opposite directions during the passage of successive series of 20 bands.

2. A sluiceway for ore-separators, comprising a sluice; a series of depressions formed therein; and semicylindrical bands extending therefrom, in series, said bands extending 25 around the lower side of said depressions, the ends of bands of alternate series being joined, whereby the material passing over said sluice will be given a backward rotary movement, said movement being in opposite 30 directions during the passage of successive series of bands.

3. A sluiceway for ore-separators, comprising a sluice; and bands extending vertically therefrom in series, the ends of bands of alternate series being joined, whereby the material passing over said sluice will be given a backward rotary movement, said movement being in opposite directions during the passage of successive series of bands.

40 4. A sluiceway for ore-separators, comprising

ing a sluice; and semicylindrical bands extending upwardly therefrom in series, the ends of bands of alternate series being joined, whereby the material passing over said sluice will be given a backward rotary movement, 45 said movement being in opposite directions during the passage of successive series of bands.

5. A sluiceway for ore-separators, comprising a sluice; and bands extending vertically 50 therefrom in lateral and longitudinal series, the ends of bands of alternate longitudinal series being joined.

6. A sluiceway for ore-separators, comprising a sluice; and semicylindrical bands extending therefrom, in lateral and longitudinal series, the ends of bands of alternate longitudinal series being joined. 55

7. A sluiceway for ore-separators, comprising a sluice; a series of depressions formed 60 therein; and bands extending vertically therefrom in lateral and longitudinal series, said bands extending around the lower side of said depressions, the ends of bands of alternate longitudinal series being joined. 65

8. A sluiceway for ore-separators, comprising a sluice; a series of depressions formed therein; and semicylindrical bands extending vertically therefrom in lateral and longitudinal series, said bands extending around 70 the lower side of said depressions, the ends of bands of alternate longitudinal series being joined.

In witness whereof I have hereunto set my hand in presence of two witnesses.

ALEXANDER ROY MACDONALD, JR.
